UNITED STATES PATENT OFFICE.

JOSEPH B. SMYTHE, OF COATICOOK, QUEBEC, CANADA.

LIFTING-JACK.

1,019,095.

Specification of Letters Patent.

Patented Mar. 5, 1912.

Application filed June 10, 1911. Serial No. 632,511.

To all whom it may concern:

Be it known that I, JOSEPH B. SMYTHE, a subject of the Kingdom of Great Britain, and a resident of Coaticook, Province of Quebec, Dominion of Canada, have invented certain new and useful Improvements in Lifting-Jacks, of which the following is a specification.

This invention relates to lifting jacks, and particularly to that class of jacks which are known as ratchet screw jacks, and has for its object the provision of a means whereby the movable member is prevented from being accidentally lowered under a heavy load.

The invention consists in providing the edge of the bottom plate with a plurality of ratchet teeth and surrounding said bottom plate with a ring carrying spring pressed pawls adapted to engage said ratchet teeth and in inclosing this ring with a split friction band anchored in the movable member, one end of said band being adapted to be moved toward the other by means of a screw or similar device to vary the frictional contact between said band and ring.

The invention consists in certain novel features of construction and arrangement of parts which will be readily understood by reference to the description of the drawings and to the claims hereinafter given.

Of the drawings: Figure 1 represents a vertical section of a lifting jack embodying the features of the present invention, the cutting plane being in line 1—1 on Fig. 2. Fig. 2 represents a horizontal section of the same, the cutting plane being on line 2—2 on Fig. 1. Fig. 3 represents an elevation of a portion of the ring inclosing the bottom plate and showing one of the spring pressed pawls therein, and Fig. 4 represents a horizontal section of the same, the cutting plane being on line 4—4 on Fig. 3.

Similar characters designate like parts throughout the several figures of the drawings.

In the drawings, 10 represents a suitable base supporting a stationary standard 11 over the outer periphery of which is fitted a movable sleeve or member 12, to the upper end of which is threaded a head 13. In the upper end of the standard 11 is mounted a non-revolute nut 14, to which is threaded a

lifting screw 15, having splined to its upper reduced end a gear 16, with which meshes a gear 17 formed upon or secured to a revolute shaft 18, the outer end of which is provided with a suitable operating mechanism 19 of any well-known construction. Interposed between the upper face of the gear 16 and the inner face of the head 13 are two annular plates 20 and 21, between which are interposed a plurality of anti-friction members 22. Between the plate 21 and the upper face of the gear 16 is preferably positioned a friction disk 23. The bottom plate 21 is provided with a plurality of ratchet teeth 24 with which engage the pawls 25 pivotally mounted in a ring 26 surrounding said bottom plate 21 and forced into engagement with said teeth 24 by means of suitable springs 25*. It is obvious that when the handle 27 of the shaft operating mechanism 19 is operated to move the gear in the direction of the arrow indicated on Fig. 2 of the drawings, the screw 15 will be so turned in the nut 14 as to cause the member 12 to be lifted relative to the standard 11, and during this rotation of the gear 16 the friction between the plate 21 and said gear 16 caused by the interposition of the friction disk 23 will be such as to cause the plate 21 to rotate with said gear. The ratchet teeth 24 on the lower plate 21 are so constructed that during this movement the lower plate 21, gear 16, and screw 15, will all turn together freely, the pawls 25 being forced into their recesses against the tension of the spring 25* as the toothed plate 21 revolves, the ring 26 being prevented from moving by the friction band 28 surrounding its periphery and contacting therewith. This friction band 28 is provided with a lug 29 positioned in the recess in the inner wall of the casing of the member 12, and diametrically opposite this lug 29 the band is split and provided with two outwardly extending lugs 30 also positioned in a recess in the inner wall of said movable member 12. When the inner wall of the band 28 is in normal contact with the periphery of the ring 26, the lugs are slightly separated.

Threaded to the casing of the movable member 12 is a threaded member 31, the inner end of which bears against one of the lugs 30. It is obvious that by turning this

threaded member 31 the ends of the band 28 may be forced toward each other, thereby making a firmer frictional contact between the band 28 and ring 26. The lugs 29 and 5 30 anchor the friction band and prevent any movement in either direction during the operation of the jack. When lowering the movable member 12, the teeth 24 on the bottom plate 21 engage with the pawls 25 10 and cause the ring 26 to rotate therewith, the movement of this ring 26 being retarded to a greater or less extent in accordance with the degree of frictional contact of the band 28 with its periphery. The ball bearing 15 jacks now in use have a tendency to run down when worn or when the load is jarred, but this objection is entirely overcome in the present invention by the friction between the movable band 28 and the pawl ring 26. 20 Owing to this tendency to run down the pitch of the threads of the screw is necessarily limited, and as they have to be returned to the lowest position by hand the operation is necessarily very slow. In the 25 present invention, however, by having the bottom plate provided with ratchet teeth on its periphery which coöperate with the pawls carried by a ring, the movement of which is controlled by a brake band, a very rapidly 30 moving screw may be used. Obviously, by adjusting means such as the threaded member 31, the brake band may be either tightened sufficiently to prevent the screw from running down or locked so that no jarring 35 or wear can cause an accident, while, at the same time, a simple adjustment of the threaded member 31 will decrease the frictional contact between the band 28 and ring 26 after the load has been blocked up or the 40 job completed to permit the screw to run down by its own weight into a normal position preparatory to another lifting operation. While a threaded member is shown in the drawings to regulate the frictional contact 45 between the band 28 and the ring 26, it is obvious that other well-known devices may be used equally as well without altering the principles of the present invention. When desired, this screw 31 or other adjusting device may be instantly removed from the jack so that the jack would be inoperative, it being self-evident that the jack will not hold any load whatever without the application of some friction to the ring 26 on 50 account of the coarse pitch usually used in a jack of this character.

It is believed that the operation and many advantages of the invention will be thoroughly understood from the foregoing.

60 Having thus described my invention, I claim:

1. In a lifting jack, the combination of a stationary member; a movable member thereon; a screw for said movable member; 65 means for rotating said screw; a plate car-

ried by said screw; a plate carried by said movable member; anti-friction members interposed between said plates; and adjustable mechanism for creating a variable friction on said screw plate.

2. In a lifting jack, the combination of a stationary member; a movable member thereon; a screw for said movable member; means for rotating said screw; a plate carried by said screw; a plate carried by said movable member; anti-friction members interposed between said plates; a ring surrounding said screw plate; means interposed between said ring and plate to insure their simultaneous movement in one direction; and a non-revolvable friction band surrounding said ring. 70 75 80

3. In a lifting jack, the combination of a stationary member; a movable member thereon; a screw for said movable member; means for rotating said screw; a plate carried by said screw; a plate carried by said movable member; anti-friction members interposed between said plates; a ring surrounding said screw plate; means interposed 90 between said ring and plate to insure their simultaneous movement in one direction; a non-revolvable friction band surrounding said ring; and means for adjusting said band to regulate its frictional contact with said ring. 95

4. In a lifting jack, the combination of a stationary member; a movable member thereon; a screw for said movable member; means for rotating said screw; a plate carried by said screw; a plate carried by said movable member; anti-friction members interposed between said plates; a ring surrounding said screw plate; means interposed between said ring and plate to insure their simultaneous movement in one direction; a non-revolvable friction band surrounding said ring provided with projections positioned in 100 105 depressions in the jack casing.

5. In a lifting jack, the combination of a stationary member; a movable member thereon; a screw for said movable member; means for rotating said screw; a plate carried by said screw; a plate carried by said movable member; anti-friction members interposed between said plates; a ring surrounding said screw plate; means interposed between said ring and plate to insure their simultaneous movement in one direction; a non-revolvable split friction band surrounding said ring; and means connecting the ends of said split band for regulating the 110 115 120 frictional contact with said ring.

6. In a lifting jack, the combination of a stationary member; a movable member thereon; a screw for said movable member; means for rotating said screw; a plate carried by said screw; a plate carried by said movable member; anti-friction members interposed between said plates; a ring sur- 125 130

rounding said screw plate; means interposed between said ring and plate to insure their simultaneous movement in one direction; a non-revolvable split friction band surrounding said ring; and a screw connecting the ends of said split band for regulating the frictional contact with said ring.

Signed by me at 4 Post Office Sq., Boston, Mass., this 19th day of May, 1911.

JOSEPH B. SMYTHE.
